UNITED STATES PATENT OFFICE

96,411

DESIGN FOR A STORAGE BATTERY STAND

Earl E. Pease, Oak Park, Ill., assignor to Battery
Patents Corporation, Chicago, Ill., a corporation
of Illinois

Application November 19, 1934, Serial No. 54,070
Term of patent 7 years

To all whom it may concern:

Be it known that I, Earl E. Pease, a citizen
of the United States of America, residing in Oak
Park, in the county of Cook and State of Illinois,
have invented a new, original, and ornamental
Design for a Storage Battery Stand, of which
the following is a specification, reference being
had to the accompanying drawing, forming a
part thereof, in which:—

The figure is a perspective view of a storage
battery stand showing my new design.

I claim:

The ornamental design for a storage battery
stand substantially as shown.

EARL E. PEASE.
